UNITED STATES PATENT OFFICE.

ANDREW TRUST POEHLMANN, OF CATONSVILLE, MARYLAND.

DESIGN FOR A KNOB FOR SIGNAL-BELLS.

50,665.

Specification for Design.

Patented Apr. 24, 1917.

Application filed January 15, 1917. Serial No. 142,571. Term of patent 14 years.

To all whom it may concern:

Be it known that I, ANDREW TRUST POEHLMANN, a citizen of the United States, residing at Catonsville, county of Baltimore, State of Maryland, have invented a new, original, and ornamental Design for a Knob for Signal-Bells, of which the following is a specification, reference being had to the accompanying drawing, forming part thereof.

Figure 1 is a front elevation of the knob, the bell being shown by dotted lines.

Fig. 2 is a side elevation.

Fig. 3 is a rear elevation.

Fig. 4 is a plan view.

I claim:—

The ornamental design for a knob for signal bells, as shown.

ANDREW TRUST POEHLMANN.

Witnesses:

R. GILBERT SKILLMAN,
JOHN H. DAMES.
